ENVELOPE TRANSFER AND FEEDING
MECHANISM

Abraham Novick, Flushing, N. Y., assignor to
F. L. Smithe Machine Co., Inc., New York,
N. Y., a corporation of New York

Application July 6, 1936, Serial No. 89,083
Renewed November 10, 1938

22 Claims. (Cl. 271—1)

This invention relates to the fabrication of envelopes and similar planiform articles, especially to mechanism for transferring or feeding such articles seriatim from stack formation, and more particularly the invention has for an object to provide for effecting the transfer individually of each article at a time when it occupies the top-most position in a stack of the articles, continuously maintained at a constant level by suitable means.

Another object of the invention is to provide for the initiation of such successive transfers by elevating each article in an arcuate path to a higher level at which it is delivered tangentially to conveyor means running in a substantially right-line path, at substantially right-angles to the axis of the stack, and which run the planiform articles are re-aligned and advanced for further fabrication as individuals, following one another in said last-named path.

A cognate object is to provide a series of cooperating instrumentalities for individualizing the articles, including separating means to free an edge of each blank as it reaches the top of the stack, a sucker to elevate this free edge, one or more oscillating arms to take the free edge from the sucker and feed it against a rotor the periphery of which defines the arcuate transfer path, and the series of rollers between which and the rotor the free edge is first engaged and eventually the entire blank is advanced and its individualization completed, these instrumentalities being so coordinated as to accomplish the transfer with unusual speed and freedom from error.

Still another object is to provide a novel and improved means for actuating transfer rotors of the above-mentioned type in a machine of the class described, with means for varying their speed ratio in conjunction with cooperating instrumentalities; also improved devices for separating the individual blanks from the rotors as they approach the region of delivery to the aforementioned right-line tangent run of mechanism; and means for effecting accurate alignment as the blanks are transferred to the chain-belt conveyor on this run.

A further general object of the invention is to provide for sturdy construction of the respective instrumentalities so that the machine as a whole will be light-running at high speeds; also to so organize the controlling cams, levers, gears, and other instrumentalities that they will be readily adjustable, and will be exposed for inspection and replacement whenever occasion may arise.

Further and more specific objects, features and

advantages will more clearly appear when the specification hereinafter is considered and is taken in connection with the accompanying drawings which form part of the specification and well illustrate a present preferred form which the invention may assume.

In the drawings:

Fig. 1 is a view in vertical, sectional elevation of a somewhat schematic character, illustrating a feed or transfer mechanism embodying the present invention as applied to a machine for fabricating envelopes and like planiform articles;

Fig. 2 is a fragmentary, detail view in vertical sectional elevation of a cam device and associated mechanism for effecting timed operation of certain of the working parts;

Fig. 3 is a fragmentary, detail view of part of a tensioning means for an aligning belt;

Fig. 4 is a fragmentary, detail view in elevation, with a portion sectioned, of two of the feeding rotors provided for transferring the articles in an arcuate portion of their path;

Fig. 5 is a view in rear elevation of the transfer mechanism as shown in Fig. 1;

Fig. 6 shows the same in plan;

Fig. 7 is a view in side elevation of the mechanism illustrated in Fig. 6, certain supporting parts, including the frame, being omitted for clearness of illustration;

Fig. 8 is a similar view showing the working parts in another operative position;

Figs. 9 and 10 are views of a similar character each illustrating a distinctive operative position of that part of the mechanism which is shown in Fig. 7;

Fig. 11 likewise shows one position of the foregoing mechanism;

Fig. 12 is a fragmentary detail view in vertical section of a series of gears illustrated in their assembled position of association with driven shaft and sleeve elements, upon which the rotors are mounted adjustably.

Generally and briefly considered in its broader aspects, the invention involves the combination in a mechanism for transferring or feeding planiform articles such as envelope blanks, with a means for supporting a stack of said articles in a given upright path, and means for elevating a stack of the articles to bring each successively to a constant level stop at the top of the path, of a means for transferring each successively topmost article individually in an arcuate path to a higher level, and thence to a tangent extension of said path, there to be delivered seriatim for further fabrication.

35

40

45

55

The general organization of the instrumentalities provided for these purposes is shown in Figs. 1, 2, 5 and 6, referring particularly to which figures at present, the part designated generally by the reference character F is the frame of the machine, comprising side members 11 and 12, cross rods 14—20, etc., and shafts to be described, hereinafter, while S designates generally an assembly of planiform articles, in this instance envelope blanks in stack formation, intended to be replenished constantly in order that during the operation of the mechanism there may be substantially an uninterrupted succession of blanks in the position indicated in Fig. 1.

15 The topmost blank S is shown as engaged with a stop-rod 22 mounted in arms 23 provided with adjusting devices, as at 24, by which the stop may be set at a constant level to define the correct position of each successive blank for operation 20 thereupon by the various working mechanisms.

Suitable elevator mechanism is indicated schematically at P which designates a platform on which the stack S may be advanced upwardly by known or suitable mechanism, as for example 25 that disclosed in my co-pending application, Serial No. 89,085 filed July 6, 1936.

In pursuance of the present invention, the blanks are removed seriatim from the stack S, by means now to be described. The blanks are acted 30 upon in turn, first by a combined hold-down and separator device (Fig. 7) including a yoke-shaped finger 25 at the end of an arm 26 held adjustably in a clamp 27 fitted upon a rock-shaft 21 journaled in the side frame member 12, and also 35 supported by bearings 29 supported by a bracket 39. The arm 26 is oscillated with shaft 21 by a series of cranks and links 30—33 to be described, it being sufficient at present to note that this motion is energized by a disc cam C' on a shaft 40 35.

Means are provided to hold the forward edges of the blanks in suitably aligned position to be 45 acted upon by the finger 25, and for this purpose I have shown a pair of adjustable abutment posts 36, carried by slotted brackets 37 bolted, as at 34, to the brackets 39 depending from cross-rods 18, 19.

Each topmost blank s as it is separated at its forward edge from the stack S, is picked up by 50 a transfer member T including a sucker nozzle N, the disposition of which for the pick-up operation is best seen by reference to Fig. 8. This nozzle constitutes the leading end of a tubular sucker arm, designated generally T, which is connected 55 with a flexible hose t (see Fig. 1) leading from a suitable source of suction (not shown).

The sucker tube T is held adjustably in a split clamp 44 by which all of the motions necessary for operation of the sucker are communicated to 60 the sucker nozzle. The supporting and operating means for the sucker arm clamp comprise various levers, links and springs, including a lever 41, hereinafter called the first transfer lever, for the sake of brevity, which is fixed upon, and oscillated by, a rock-shaft 43 and is connected pivotally with the clamp 44 as at 46.

A control link 42 is connected pivotally, as at 48, to a lug 49 of clamp 44, and acts to govern the movements of the sucker arm, being fixed at 70 its other end to bracket 39, as by an eccentric screw stud or pin 51 (see Fig. 1) set in a sector 52, with a slot 53 and set-screw 54 to permit adjustment of the range of throw of the sucker T, in correspondence with the top position of the 75 topmost blank s as determined by adjustment of

stop rod 22. The sector 52 is centered on a larger stud 56 (Fig. 1) set in the bracket 39, and has a handle 55 to facilitate its manipulation.

Oscillation of the shaft 43 is produced preferably by means best illustrated in Figs. 1 and 2, 5 and which may be described advantageously at this point in the specification. The means shown comprise a cam C'' on cam shaft 58 which is driven by pinions 59, 60 of which the latter is journaled on a short shaft 61, mounted on frame member 11 and provided with a sprocket wheel 62 driven by a chain belt 63 running from a suitable source of power (not shown). It may be noted, in passing, that the shaft 58 is also fitted at each end (see Figs. 1 and 5), with a gear 64, 15 64' the former of which is meshed with an intermediate gear 65 acting to drive a pinion 66 on the shaft 67 by which the straight-line conveyor belts or chains 68 are actuated to effect final removal of the articles upon completion of transfer according to the present invention.

The cam C'', accordingly, rotates with the shaft 58, and as means to make the cam C'' effective to oscillate the shaft 43, a follower roller 57, engaged with the periphery of the cam C'', is connected, by a link 70 and arm 71, with the shaft 43, the follower being mounted, as at 71, upon an arm 7 pivoted upon a stud 6. An arm 5 is rigid with the arm 7 and has connected thereto, at its free end, a coil spring 4 stretched from a post 3 on the frame member 11, and acting to bias the follower roller 57 against the cam C''. When the roller 57 is engaged with either of the high lumps c', c'' of the cam C'', (see Fig. 2) the sucker T occupies a retracted high position, as indicated at T in Fig. 2, and similarly in Fig. 11; from which the sucker is urged to descend as the low region c³ of the cam C'' turns past the roller 57, and after the sucker nozzle N has been engaged operatively with the topmost sheet s of the stack (see Fig. 8), the sucker is raised, lifting the forward, free end 2 of the blank s with it.

This elevation of the free end of the article is shown in Figs. 9, 10 and 11, and these figures illustrate means which continue the elevation of the free end until it is engaged with the periphery of the feeder rotor discs R¹—R⁶, shown in a parallel series best seen in Fig. 6.

To accomplish this stage of the transfer operation, a pair of rollers 73 are shown (see Figs. 6—11 inclusive) each carried by a system of arms 74, 75, 76, the parts 74 and 75 being integral with each other preferably forming a knee at 77, where a pivot stud is provided, to be described later herein. The upper end of each lever arm 75 is pivotally jointed at 78 to the uppermost part 76 of the series, the latter being provided with a slot 79 to slide freely on a stud 80. These studs, as illustrated in Fig. 1, are set, each in an extension 81 of one of the brackets 39. A coil spring 82, extended between each pivot 78 and a lug 83 on the part 84 of bracket 39, tends to draw its connected toggle joint 78 constantly toward the position shown in Fig. 1 and Fig. 11, at which position the rollers 73 are acting to press the free end 2 of the blank s against the rotors R³, R⁴, so that rotation of the latter will advance the blank upwardly in an arcuate path in which it is maintained by passing successively into the bite of rollers 85, 86 and 87, (see Figs. 1 and 5) urged against the periphery of rotor R³ by the action of coil springs 88 against plates 89 of yokes 90 pivotally mounted at 91 upon brackets 92 mounted between guide arms 114 extending from the cross-bar 16, (Fig. 1). In the system 75

of each compound floating lever 74, 75 and 76, the pin 77 at the "knee" part between arm parts 74, 75, is formed as a headed stud secured to the rotatable member 93 associated with cam C' (see Figs. 5 and 6) and is thus adapted to be swung toward and away from the rotors R³, R⁴ as the shafts 28 are turned by rotation of the gears 94, 64 and 64' (see Fig. 6 and Fig. 12), the gears 64 and 64' being fast on the shaft 58.

It is to be noted that the final pressure of rollers 73 against the middle pair R³, R⁴ of rotor discs is effected against the action of springs 82 (see Fig. 1) in breaking the toggle joints at 78, and at that time the short links 76 are pressed to the position shown in Fig. 1 from that shown in Fig. 11, this shift being permitted by the clearance in slots 79. When the compound levers 74, 75, 76 are free to be retracted to the position shown in Fig. 9 for shifting the roller 73 preparatory to picking up the end 2 of blank s which is being held by the sucker nozzle N as shown in Fig. 9, the springs 82 act to draw the links 76 rearward and downward and maintain them there, as shown in Figs. 9, 10 and 11, with a slight change of position upward, as made evident in Fig. 11.

When the blank s has been carried around through the arcuate path defined by the periphery of the rotors R'-R⁶ to the upper level defined in Figs. 1 and 6 by the comb-like stripper-plate 100, the teeth 101 thereof strip the blank from the rotors and shift it to the parallel chains 68, on which are provided studs 98 adapted to enter the incut angles between the flaps, for the purpose of aligning the envelope blanks as they are advanced for delivery from the mechanism.

Suitable auxiliary hold-down or guide means are provided, as indicated at 113, 114 and 115, above the blanks, and an auxiliary advancing and aligning means 102 is also desirably provided as shown in Figs. 1 and 6, taking the form of a belt running over a pulley 103 rotatably mounted on a shaft 104 fixed adjustably in a slot 105 of a bracket 106 which is attached by a lug 107 to a cross-bar 17 of the frame (see Fig. 3). The bracket has a curved upper margin 108 which extends upward to a height suitable to act as a side guide for the belt 102 (see Fig. 6) and the other side of the belt is guided by a curved member 109 which is extended at 110 alongside of a trough-like part 111 adapted to receive the belt 102. This belt member may be driven positively, as by a suitable pulley at its other end (not shown) and at such a speed relatively to the chains that the blanks are sufficiently retarded to insure proper engagement of the blanks with the chain studs 98. An overhead drag device of known form (not shown) may also be provided to aid in effecting this alignment.

In Fig. 4 is shown a preferred structure of the rotors R³ and R⁴ which are therein illustrated as

provided with friction surfaces 112 of suitable flexible, elastic material, such as rubber.

As has been briefly described above, means, comprising blades 113, 114, 115, 117' and 117'',

are provided for holding the blanks down upon the rotor discs R'-R⁶ in such a manner as to

secure uniformity of feeding movement. These blades, curved in the form of a sickle, are carried by the cross member 16 spanning the space be-

tween the side members 11 and 12 of the frame.

Thumb screws 118 are provided to fix clamps 116,

holding the blades 113, 114 and 115 in adjusted

positions laterally upon the cross-rod 16, and at

least one of the guide-blades, as 114, will prefer-

ably be curved suitably as illustrated in Fig. 5

to avoid interference with, and by, the working parts at the center of the machine. The blades 117' and 117'', which support the brackets 91 and 92, are mounted upon a block 117 secured to the cross-bar 16 by a bolt 117x.

The preferred means for actuating the rotors R' to R⁶ is illustrated in Fig. 12, where two of the rotors, viz., R² and R⁵ are shown illustratively as typical members of the series, the shaft 58 and its associated parts being broken away at intervals to permit condensation of the figure. A sleeve 158 is provided upon, and rotatable independently of, the shaft 58, and upon this sleeve are fixed, as by set-screws R, the hubs of the several rotors. The sleeve is rotated through back gearing 165, 165 and 164, from the gear 64, the last named gear being splined, as at 64x, to the shaft 58, while the gear 164 is fixed, as by a set screw 164x, to a terminal 166 of the sleeve 158 which overlies, and runs freely, upon a like co-axially disposed extension 157, of the hub 168 of the gear 64. The gear 165 is fast upon the hub 169 of the gear 65, so rotates at the same speed, and the gear 165, which is of the same diameter as gear 64, but has one less tooth, is mounted upon a long stud-bolt 170, set in an aperture 171 of the frame member 12, as shown in Fig. 12, so that the gear 164 and sleeve 158 rotate at a slightly lower speed than the shaft 58.

The effect of this difference in timing is to avoid an undesirable repetition of contacts by the rollers 73 with the same point on the peripheries of the rotors when swung thereagainst by the arms 74. It will be understood, of course, that this desired effect can be produced either by a faster or slower timing of the rotors.

It will be seen from the foregoing that the mechanism constituting the subject matter of the above disclosure is adapted to operate upon different sizes and shapes of envelopes or like planiform articles; and that in conjunction with suitable means for supplying blanks in stack formation continuously to a predetermined stop, the mechanism herein described is adapted to transfer the individualized envelopes or other blanks and deliver them rapidly, continuously and accurately in a right line run for any operation which may be performed advantageously upon such articles while being advanced successively along a right line path in the plane of their greatest dimension.

The manner in which the novel mode of transfer lends itself to speedy delivery in the same undivided order from a stack assembly may be made more apparent by a resume of the steps comprising the transfer operation, as follows:

Starting with the parts in the relative positions illustrated in Fig. 7, the top blank s of the stack S is ready for transfer, but is still held down by the member 25, while the sucker nozzle N is in its elevated position, where it has remained since the preceding blank was lifted by it; and the rollers 73 are still in approximately the position to which they were moved in shifting the preceding blank from the suction nozzle to the rotors R³, etc.:

In Fig. 8, the sucker nozzle N has advanced to its position of engagement with the topmost blank s, the hold-down fingers 25 are being retracted and the rollers 73 have descended to a position where they clear the path for upward lift of the forward edge of the blank s and are ready to be swung under the lifted edge:

In Fig. 9 the sucker N is illustrated as having lifted the forward edge 2 upward past the hold-

down 25, which has been further retracted, and while the rollers 73 dwell, owing to the position of pins 77, whose connections with rotating member 93 permit the feed levers 74-75 to retain 5 substantially their stationary position:

In Fig. 10 the levers 74-75 are moved forward under the free edge 2 of the blank, which has been released by cutting off the suction from nozzle N, and the parts are now ready to shift the 10 edge 2 over against the periphery of the rotors R', etc.:

In Fig. 11 this shift has been accomplished, and the rollers 73 are positively held toward the periphery of the rotors R³ and R⁴ by the action of 15 the levers 74-75, (Fig. 1) the springs 82 exerting a yielding bias upon the rollers 73 by breaking the toggle at 78, and rocking the lever 74-75 around its pivot 71, this yielding restraint permitting the pivot 71 to raise the lever 74-75 upward 20 under control by the link 76, so that the lever floats and accommodates itself to various thicknesses of blanks without the need for special adjustments:

During the above shifting operation, the sucker 25 nozzle N has been raised to an upper position and the hold-down 25 has again descended to its operative position of engagement with a top blank s of the stack:

Reverting again to Fig. 1, it will be seen that 30 as the rollers 73 accompany the body of the blank for a certain distance in its arcuate path defined by the circumference of the rotors R³, etc., the levers 74-75 tend to be rocked against the bias of springs 82, and this counter-rocking action is 35 permitted by the play of slotted part 79 upon stud 80. The lever systems 74-75-76 accordingly afford a very sensitive but firm means for co-operating in the feeding of each blank in turn as it runs upward between the rotors and the series 40 of rollers 85, 86 and 87, being delivered thereby to the co-operating action of belt 102 and chains 68, by the studs 98 of which the individualized blanks are aligned in the manner already described.

45 I have described what I believe to be the best embodiments of my invention. I do not wish, however, to be confined to the embodiments shown, but what I desire to cover by Letters Patent is set forth in the appended claims.

50 I claim:

1. In a mechanism for transferring planiform articles such as envelope blanks, of the class comprising means for supporting a stack of said articles in a predetermined upright path, and 55 means to elevate the stack to bring each article therein successively to the topmost position of the stack at a constant, predetermined level; means for transferring each such successively topmost article individually in an arcuate path to 60 a higher level, and thence to a tangent extension of said arcuate path, there delivering the articles seriatim for fabrication or further treatment, said means including a feeding rotor, an oscillating lever movable intermediate the top of the 65 stack and the rotor to press the separated end of a blank against the rotor, a separator means to effect said separation and present a free blank end in the path of said lever, and a series of rollers spaced around said rotor and adapted to 70 cooperate therewith upon the blank to advance it in said arcuate path to said point of tangent delivery.

2. A transfer mechanism comprising the instrumentalities combined and cooperating as set 75 forth in claim 1, and further characterized by

having a right-line conveyor means to which said blank is delivered from said rotor.

3. In a mechanism for transferring planiform articles such as envelope blanks, of the type comprising means for supporting a stack of said articles in a predetermined upright path, and means to elevate the stack to bring each article therein successively to the topmost position of the stack at a constant, predetermined level; and means for transferring each such successively topmost article individually in an arcuate path to a higher level, and thence to a tangent extension of said arcuate path, there delivering the articles seriatim for fabrication or further treatment; said transfer means being characterized by including an oscillating sucker arm to lift the leading edge of said topmost blank from the stack, a rotor and a series of spaced complementary rollers by which said arcuate path is defined and an intermediate transfer arm to receive said leading edge from said sucker device and shift it to said rotor.

4. A mechanism of the class described, comprising the elements combined and cooperating as set forth in claim 3, and further characterized by having said transfer arm adapted to hold said leading edge yieldingly against said rotor until its advance in the arcuate path is assured.

5. In a mechanism of the class described, including a feeding rotor, a transfer arm formed 30 of a series of components including a two-part toggle lever having a medial pivot spring biased to a broken position in which the free end of the arm series is urged toward said rotor.

6. A mechanism of the class described comprising the elements combined and cooperating as set forth in claim 5, and further characterized by having one end of said two part toggle-lever provided with a pin-and-slot fulcrum adapted to permit shifting of said arm structure bodily under 40 the urge of said spring-bias.

7. A mechanism of the class described, comprising the elements combined and cooperating as set forth in claim 3, and further characterized by having said sucker device formed with a clamp 45 in which a sucker nozzle is adjustable lengthwise, an oscillating supporting arm for said clamp, mounted on a rack-shaft, and a control-link connected to said clamp and anchored to a fixed support.

8. A mechanism of the class described, comprising the elements combined and cooperating as set forth in claim 3, and further characterized by having said sucker device formed with a clamp in which a sucker nozzle is adjustable lengthwise, 55 an oscillating supporting arm for said clamp, mounted on a rack-shaft, and a control-link connected to said clamp and anchored to a fixed support, said anchorage including a sector mounted on an eccentric pivot, and adapted to control the throw of said control link and sucker adjustably.

9. A mechanism of the class described, comprising the elements combined and cooperating as set forth in claim 3, and further characterized 65 by having said sucker device formed with a clamp in which a sucker nozzle is adjustable lengthwise, an oscillating supporting arm for said clamp, mounted on a rack-shaft, and a control-link connected to said clamp and anchored to a fixed support, and means to rock said shaft reciprocatingly, comprising a cam, means to rotate said cam, a bell-crank lever having a cam-follower at the free end of one arm, a tension spring connected with the free end of the other arm of said bell- 70 75

- crank lever, and adapted to urge the cam-follower against said cam, an arm on the rock-shaft, and a link connecting said rock-shaft arm with said follower arm.
- 5 10. A mechanism of the class described, comprising the elements combined and cooperating as set forth in claim 1, and further characterized by having said rotor formed as a series of rotor discs mounted in parallel spaced-apart disposition on a common shaft.
- 10 11. A mechanism of the class described, comprising the elements combined and cooperating as set forth in claim 1, and further characterized by having said rotor formed as a series of rotor discs mounted in parallel spaced-apart disposition on a common shaft, some of said rotor discs having an elastic friction periphery.
- 15 12. A mechanism of the class described, comprising the elements combined and cooperating as set forth in claim 1, and further characterized by having said rotor formed as a series of rotor discs mounted in parallel spaced-apart disposition on a common shaft, and a stripper device comprising a comb-like member extended in parallelism with said shaft adjacent to the peripheries of said discs and including pointed teeth extending respectively into the spaces between said discs.
- 20 13. A mechanism of the class described, comprising the elements combined and cooperating as set forth in claim 1, in which the rotor includes a series of discs, and further characterized by having a table-like guide means disposed to overhang said blanks as they pass from said rotor discs, a plurality of chain belt conveyors spaced apart laterally, and provided with aligning studs, and an auxiliary aligning belt device disposed intermediate said chain conveyor belts and adapted to be engaged frictionally with the under surfaces 25 of the blanks to retard the same yieldingly to aid in causing engagement of the blanks with said aligning studs at each side compensatingly.
- 25 14. A mechanism of the class described, comprising the elements combined and cooperating as set forth in claim 1, and further characterized by having a series of knife-like guide blades disposed at intervals across the periphery of said rotor.
- 30 15. A mechanism of the class described, comprising the elements combined and cooperating as set forth in claim 1, and further characterized by having a series of knife-like guide blades disposed at intervals across the periphery of said rotor, at least one of said blades being curved intermediate its ends to avoid interference with co-acting elements of said mechanism.
- 35 16. A mechanism of the class described, comprising the elements combined and co-operating as set forth in claim 1, and further characterized by having said rotor formed as a series of rotor discs mounted in parallel spaced-apart disposi- 40
- tion on a common sleeve, a shaft on which said sleeve is mounted, and means to rotate said shaft and sleeve respectively at a desired ratio relatively to each other.
- 45 17. A mechanism of the class described, comprising the elements combined and co-operating as set forth in claim 1, and further characterized by having said rotor formed as a series of rotor discs mounted in parallel spaced-apart disposition on a common sleeve, a shaft on which said sleeve is mounted, and means to rotate said shaft and sleeve respectively at a desired ratio relatively to each other, said last-named means including back-gearing connecting said shaft and sleeve.
- 50 18. A feeding mechanism of the class described, comprising in combination a rotor, means to drive the same, a feeding arm adapted to be swung toward and away from the periphery of said rotor from time to time to feed thereagainst in succession a multiplicity of blanks for advancement between said rotor, and the end of the arm by rotation of the rotor, and means for causing said swinging movements of the arm, said last-named means and the driving means for said rotor being so co-ordinated that the successive engagements of the rotor by said arm occur at regions of the rotor's periphery suitably varied to avoid undue wear.
- 55 19. A feeding mechanism comprising the elements combined and co-operating as set forth in claim 18, and further characterized by a shaft, means to rotate said shaft at predetermined speed, a sleeve on said shaft and carrying said rotor, and back-gearing connecting said shaft and sleeve, said back-gearing having a tooth-ratio suitable to enable said shaft to drive said sleeve and rotor at the intended different speed relatively to the speed of rotation of said shaft.
- 60 20. A feeding mechanism comprising the elements combined and cooperating as set forth in claim 18 in which a link is pivotally secured to one end of said feeding arm, said arm and link together forming a toggle joint.
- 65 21. A feeding mechanism comprising the elements combined and cooperating as set forth in claim 18 in which the feeding arm has an intermediate knee portion and the means for causing swinging movements of the arm comprises a rotary member pivotally connected to said knee portion.
- 70 22. A feeding mechanism comprising the elements combined and cooperating as set forth in claim 18 in which the feeding arm consists of a lever pivotally mounted at an intermediate point on the means which causes its swinging movements and further characterized by having a link connected to one end of said lever and yielding means for constantly urging the end portion of the lever towards the rotor.

ABRAHAM NOVICK. 60
